UNITED STATES PATENT OFFICE

154,553

DESIGN FOR A NURSERY BOTTLE WARMER

Roy H. Lesner and William J. Vignola,
Chicago, Ill.

Application April 6, 1948, Serial No. 145,558

Term of patent 3½ years

(Cl. D81—10)

To all whom it may concern:

Be it known that we, Roy H. Lesner and William J. Vignola, both citizens of the United States, residing at Chicago, Illinois, in the county of Cook and State of Illinois, have invented a new, original, and ornamental Design for a Nursery Bottle Warmer, of which the following is a specification, reference being had to the accompanying drawing, forming part thereof.

Fig. 1 is a top plan view of a nursery bottle warmer, showing my new design.

Fig. 2 is an end view; and

Fig. 3 is a side elevational view thereof.

I claim:

The ornamental design for a nursery bottle warmer, as shown.

ROY H. LESNER.
WILLIAM J. VIGNOLA.
